UNITED STATES PATENT OFFICE.

ARTHUR E. SPINASSE, OF MOUNT VERNON, OHIO.

APPARATUS FOR DRAWING GLASS CYLINDERS.

1,361,635.

Specification of Letters Patent.

Patented Dec. 7, 1920.

Application filed September 15, 1915. Serial No. 50,823.

To all whom it may concern:

Be it known that I, ARTHUR E. SPINASSE, a citizen of the United States, residing at Mount Vernon, in the county of Knox and 5 State of Ohio, have invented certain new and useful Improvements in Apparatus for Drawing Glass Cylinders; and I do hereby declare the following to be a full, clear and exact description of the invention, such as 10 will enable others skilled in the art to which it appertains to make and use the same.

The invention relates to new and useful improvements in an apparatus for drawing glass cylinders, and has for an object to provide means whereby a single motor may be utilized for operating the drawing means for drawing the cylinder, and also the generating means for generating air for the formation of the cylinder, whereby any variations 15 in the speed of the motor, thus varying the speed of draw, will likewise vary the amount of air supplied to the drawing means.

A further object of the invention is to 20 provide means whereby the speed of the motor may be regulated.

A still further object of the invention is to provide means whereby the regulation of the speed of the motor is controlled by the 25 position of the bait of the drawing means to which the cylinder is attached.

These and other objects will in part be obvious and will in part be hereinafter more fully disclosed.

30 35 In the drawing:

Figure 1 represents in outline my entire apparatus.

Fig. 2 is a side view of the hoisting drum.

Fig. 3 is a side view of one form, and

40 Fig. 4 a sectional view of another form of joint employed in my air conduit.

Fig. 5 is a diagram showing a modified way of mounting my articulated section of pipe.

45 Fig. 6 is a plan view of the rheostat which I employ.

Fig. 7 is a side view of the blower employed.

Fig. 8 is a front view in detail of the 50 drawing carriage and attachment thereto.

Fig. 9 is a section through the line A—A in Fig. 11.

Fig. 10 is a view of a modified form of means for attaching the feed.

55 Fig. 11 is a view of the drawing carriage

showing an attachment of an injection jet for blowing the cylinder.

In these drawings like letters of reference indicate like parts.

I preferably use two jointed or articulated arms or pipe sections 1 and 2, of about equal length, and each slightly longer than one-fourth of the length of the article or cylinder to be drawn. One of these arms, which is the final end of the air conduit, is 55 pivoted, as at 3, to the carriage 4, which slides upon the uprights 5 in the production of the cylinder.

The sign 6 represents a winding drum around which is wound the rope or cable 52, 70 the other end of which is attached to the drawing carriage. At 7 occurs the first joint in my articulated pipe. This joint occurs between one section of the articulation and a fixed part of the pipe, and is therefore a fixed joint. This joint corresponds in some respects to the shoulder joint of the human arm, and the joint 3 to the wrist joint. Between these joints is the joint 23, 75 which corresponds to the elbow joint of 80 the arm.

The shoulder joint 7 is located about half way up the traverse of the drawing carriage, so that while the joint 3 is passing from its lowest to its highest point, the two 85 members 1 and 2 will be swung about their pivots 23 and 7. These joints are always free and open, as shown in Fig. 4 particularly, for the free passage of air.

The upper member of the articulation 1 I 90 preferably extend in an arm 8, through which air may not pass. This arm or lever extension 8 is adapted to move over the contact points of the adjustable rheostat 9 which is in the shunt field 11 of a motor 10. 95

At 12 I provide a reversing switch, which is in the armature circuit, so that the motor can be reversed, if desired, for lowering the carriage. The load is controlled by the rheostat 13 in the same circuit, said rheostat also 100 serving as a switch. I connect the motor 10 by means of clutch 14 to shaft 15, and this, by means of gears 16, 17, 18, the last of which is a worm gear, to the drum 6.

At 19 I show the projecting nipple of the 105 blowing apparatus, adapted to blow air into the upper part of the bait 20, shown in Fig. 1 as in the act of starting cylinder 21 from the bath 22, which may be contained in any suitable receptacle. The bait may be, of 110

course, connected in any suitable manner. I continue the members 1 and 2 in the conduit 24 connected to the blower 25.

The effect of the blower is to feed air toward the cylinder being formed, beyond the capacity of the cylinder, and the surplus air thus fed is taken off by the controlling valves 26 and 54, which are arranged to be under the control of the operator. The overflow or valve 26 is arranged to be quickly turned by the operator for coarse adjustment. The valve 54 is used only for fine adjustment by means of the screw 56, the connecting rod 55 adjustable upon the arm or valve 54, and the wheel 57. The operator thus has the air under fine control, and can regulate the pressure down to a nicety.

If motor 10 should get out of order it is disconnected at clutch 14, and by means of clutch 27 the auxiliary or supplementary motor 28 is brought into use.

In Fig. 2 is shown, in front view, the winding drum 6, and in connection with this drum I may provide a clutch 30, operated by arm 31 pivoted to some fixed point, and to which may be connected cable 33 which extends somewhere within the reach of the operator, so that by pulling cable 33 the arm 31 is swung against spring 32 to disconnect clutch 30 from the drum, whereby the drum becomes loose on shaft 32' and the carriage is permitted to rapidly lower itself until it comes near the level of the glass, where it is stopped, a bait 58 attached to it and the switch 12 swung to give the motor downward motion until the bait becomes immersed to a sufficient depth in the body of the molten glass. The motion is then stopped, and the direction reversed by reversing the switch, and the drawing then proceeds. The rheostat 13 is adjusted and the valves 26 and 54 looked after; the rheostat 9 being automatically responsive to the position of the parts 1 and 35, which in turn is responsive to the position of the drawing carriage. By introducing greater or less resistance into the motor field, I determine the speed of the draw and the speed of the blower as well.

I may do without the clutch and may rely altogether upon the reversing switch to effect the up and down motion of the bait.

When the arm 8 on rheostat 9 nears the end of contact 34 the motor is stopped, and the drawing of the cylinder ended. The cylinder is then severed at the bottom and taken down in the usual way. The arm 1 may begin to oscillate as soon as the draw begins. I do not wish to change the speed of draw at this early stage. I therefore provide in my rheostat 9 a lengthened contact 29, so that while the arm 8 is switching over this contact the resistance in the field coils of the motor, and consequently the speed of the motor, is not changed. In consequence,

for initial period of the draw, the drawing speed, and the blower speed and generated air pressure remain constant.

The pipes 1 and 2 may be provided with a pivot at 7, which may have suitable adjustment either vertically or horizontally. The rheostat itself is adjustable.

My rheostat is adjusted or graduated so as to give a prescribed speed over a certain distance of draw, and generate air in desired quantity for a certain distance or period of the drawing. A change may take place in the speed and the draw over 30, 40 or 60 inches, more or less, as may be desired. The air pressure generated is affected accordingly, or in synchronism with the change in the drawing speed. I have shown the air and speed varied together by one set of arms 1 and 2, but I may provide means for varying them independently.

In Fig. 6 I show my preferred form of rheostat 9. As above stated, connected to the pipe 1 is an extension 8, which is the contact arm of the rheostat. This I provide with the shoe 35 which travels upon the contacts 29, 36, 37, 38, 39, 40 and 41. I do not show 29 in Fig. 6. Although, of course, the contacts may be of any number and of any proportionate size, each represents so many units of length of the cylinder being drawn.

I provide for each contact an extension 44, shown in the contact 3', and in this extension is a slot 42 through which, by means of a screw, each contact is secured to the board 43. These contacts may be arranged in any of the known ways for arranging them on rheostats.

In the rheostat here shown, each of the five contacts represents a certain part of the cylinder drawn. By this means each part of the cylinder can be referred to a certain part of the rheostat, and, should necessity for changing speed or generated air pressure arise, as determined from an inspection of the cylinder, the contacts of the rheostat can be arranged accordingly. Thus the sections numbered 1', 2', 3', and so on of the rheostat, correspond with the first, second, third, etc., sections of the cylinder.

In Fig. 6 the dotted line 45 shows the pipe 1 nearly at the end of an operation. The shoe 35 is near the end of the rheostat, and the contact 41, the final contact, may be adjusted so as to automatically disconnect beyond a certain point.

Each contact is inserted into the field as follows:

46 represents a resistance coil with a succession of buttons 59, as shown. The wire 47 is from contact 36 to the first button of the coil. Therefore the shunt field circuit is normal. When shoe 35 reaches contact 37 it cuts in six buttons of the resistance coil through the wire 49, 48. Similarly, more resistance may be cut in as the shoe pro-

ceeds. By the device arranged as shown, the rate of speed increases successively for each length up to length 4, and then it may suddenly drop to normal at the fifth length. 5 The rheostat is set to draw, say, a four length cylinder, each contact corresponding to a one length cylinder. Of course this may be varied. Therefore when contact 5' is reached the speed is reduced to normal; 10 this I indicate by dotted line 50. At this slow speed the lower part of the cylinder is separated from the glass bath either by fire or by breaking in well known manner; then more current may be added, or another 15 contact causing the motor to jump to higher speed, may be provided to further elevate the cylinder away from the glass bath preparatory to taking down the same for further treatment. 20 My automatic rheostat 9, Figs. 1 and 6, varies the speed of motor 10, and the speed of draw may therefore be infinitely varied at any stage of the draw; and since the drawing motor solely also actuates the air 25 generator the air pressure generated is always correspondingly varied with the draw subject, when they are used, to the controlling valves 26 and 54. The motor 10 is also under the control of the switch rheostat 13. 30 Of course in cutting in resistance into the shunt field circuit of motor 10, its speed is increased.

I aim to lower the speed of draw; this is of utility in severing the cylinder. 35 Sometimes the working nature of the molten glass from which the glass is being drawn may vary in such a way that, gradual decrease in the speed of draw is of great utility in maintaining even strength of wall 40 in the article drawn, and other desired results, especially when drawing is made from a glass tank.

In Fig. 10 I show a front view of carriage 4 with the parts in position. This carriage 45 slides upon the standards 5. I show pipe 2 joined to pipe 64, and this latter pipe is secured to the carriage. The angled pipe 65 is mounted to slide to the right or left on the carriage, and mounted to swing also in 50 or out from the carriage. It maintains always a telescopic connection with the pipe 64 through which the air enters. I provide at the point 66, Fig. 8, a screw attached to this pipe, and this forms one of the means of 55 support for said pipe, the other being the pipe 64. By turning the wheel 67', which is provided with a nut for said screw, I may advance or retract the screw 66, and thus advance or retract the angled pipe 65 with reference to pipe 64. This screw performs another function, moreover, since it enables me 60 to adjust the position of the bait to the right or left of the carriage by moving the said screw. I need not necessarily make the 65 said telescopic connection tight. The joint

formed by pipes 64 and 65 may, however, be made to operate flush so as to prevent the escape of the air.

I provide at 69' and 70 shoes which engage with the standards 5, and these shoes are 70 pivoted to one end of bent levers 71 mounted upon the carriage. The other end of each of these levers is connected to a retractile spring 72, as shown, so that the tension of the spring 72 has a constant tendency 75 to push the shoes 69 and 70 against the part 63 or slideway. The carriage is thus always held in firm relation to its sliding ways and does not chatter nor stick.

At 73 I show a bent portion of the angled 80 pipe 65, in which portion I mount the upper part of a bait. This bait is mounted simply by thrusting its upper end into the part or expansion 73. At 74 I show a screw mounted in the carriage and adapted to contact 85 with the part 65, above alluded to, of the pivoted angled pipe. By turning this screw I am enabled before drawing, quickly to adjust the position of the bait 58 to and from the carriage. This, taken in connection with 90 the adjustment provided by the screw 66, gives me means for adjusting the bait at any point desired, within a given area. I show attached to the bait proper in these figures, a hook or loop 75 to which a tool may be 95 attached to aid in handling the bait.

In Fig. 10 I show a modified way of attaching the bait, the drawing carriage being supplied simply with the entering pipe 64, in the mouth of which is pivoted the horizontally turned upper end of the bait. 100

In Fig. 11 I show another modification in which the pipe 64 terminates in a downwardly extending jet 68, which discharges directly into the flaring upper end 67 of the 105 bait's handle. In this form of device air should be supplied in greater quantity than in the other, because the overflow, at the jet 68 and end 67, of air is apt to be greater than in other forms; at the same time a certain uniformity is attained in this construction which is not always possible in other constructions. The bait is here shown attached directly to the carriage in the fork 69. 110

I do not wish to be limited to the precise 115 construction shown, but desire to have my invention cover all equivalents.

The drum and machinery may be to one side the glass, so as to avoid dirt falling in the glass. They may be located at a point 120 remote, and the cable held in position by means of a suitable wheel.

The rheostat also is preferably inclosed so as to avoid deposit of dust upon the contact which would have a tendency to affect their 125 operation injuriously.

From valve 54, to the carriage, bait, or rheostat, I may increase the length of my air pipes, as per A and B, for the following reason:

Air is elastic, it is well known, and I take advantage of this physical property by lengthening the air conduit, since the elastic effect of the air increases in proportion to the length of the pipe, and therefore the nicer the effect of the same to the article formed thereby.

It will be seen that by my structure I am enabled to govern the speed and draw in direct response to the position of the bait as it approaches the upper end of the draw. I place the air supply also in controlled relation to the position of the bait because it is driven by the same motor that drives the bait. It is to be observed, however, that the air pressure is not always in direct response to the speed of rotation of the fan absolutely. Hence I find it necessary, at certain periods of the draw, to provide means for varying the air supply in the valves 26 and 54. Moreover, these same valves provide means for varying the air supply in response to occasional conditions of the glass, particularly conditions of viscosity induced by some slight variation in the formula to which the batch is composed, or variations of temperature, weather, etc. That is, I provide a device which, as long as the conditions remain absolutely unchanged, automatically operates; and at the same time I provide means whereby the functioning of this device may be controlled or immediately changed to meet special needs.

I have, it will be noted, provided a single motor effecting draw and supplying air. The speed of this motor must necessarily be reduced by suitable reducing gear, to the requirements of the draw, and in coördinating the pressure and supply of air to the draw when both come from a rapidly moving motor, I effect a desirable smoothness of operation. To cut down the two simultaneously reduces variation in the cylinder drawn.

In my rheostat 9 I also provide means for changing the speed of the motor, and consequently the rate of draw, to meet varying conditions.

The invention in its broadest aspect is directed to a motor together with means operated thereby for drawing the cylinder, and a blower which is also connected to the motor so that both the drawing means and the blower are operated by one and the same motor, whereby variations in the speed of the motor will affect the speed of draw, and likewise affect the amount of air supplied for drawing purposes, and so far as this aspect of the invention is concerned, the control of the motor may be hand controlled instead of automatic. The invention is further directed to controlling means for regulating the speed of the motor, and in its more specific aspect, to the control of the speed by the movement of the bait during the drawing of the cylinder.

Having thus described my invention, what I claim as new and desire to secure by Letters Patent is:

1. In an apparatus for drawing glass cylinders, in combination, a bait, a drawing drum connected to said bait, a motor for driving said drum, an air conduit connected to said bait, a blower for supplying air to said conduit, and means whereby said blower may be connected to and driven by 75 said motor.

2. In an apparatus for drawing glass cylinders, in combination, a bait, a drawing drum connected to said bait, a motor for driving said drum, an air conduit connected 80 to said bait, a blower for supplying air to said conduit, means whereby said blower may be connected to and driven by said motor, and means whereby the speed of the drum-driving and blower-actuating motor 85 is automatically determined according to the position of the bait.

3. In an apparatus for drawing glass cylinders, in combination, a bait, a drawing drum connected to said bait, a motor for 90 driving said drum, an air conduit connected to and movable with said bait, a blower for supplying air to said conduit, means whereby said blower may be connected to and driven by said motor, a stationary rheostat 95 in the field of said motor, and means connected between said movable air conduit and stationary rheostat for varying the resistance in said motor field in accordance with the position of said bait. 100

4. In an apparatus for drawing glass cylinders, in combination, a bait, a drawing drum connected to said bait, a motor for driving said drum, an air conduit connected to said bait, a blower for supplying air to 105 said conduit, means whereby said blower may be connected to said motor, a rheostat in the field of said motor, and an arm forming an extension of a part of said air conduit and adapted to range over the contact points 110 of said rheostat in accordance with the position of that part of said conduit which is connected to said bait.

5. In an apparatus for drawing glass cylinders, in combination, a bait, a drawing 115 drum connected to said bait, a motor for driving said drum, an articulated air conduit connected to said bait, a blower for supplying air to said conduit, means whereby said motor may be connected to said 120 blower, and means whereby the speed of the motor is varied in accordance with the position of one of the members of said articulated conduit as determined by the position of the drawing head. 125

6. In an apparatus for drawing glass cylinders, in combination, a bait, a drawing drum connected to said bait, a motor for driving said drum, an articulated air conduit pivoted at one end to the drawing head 130

- and at the other end to a fixed part, a rheostat in the field circuit of the motor, and an extension on that member of the articulated conduit, next the fixed pivot, adapted to 5 sweep over the contacts of the rheostat as the position of said member last named is determined in accordance with the position of another member of said conduit as determined by the height of the drawing head.
- 10 7. In an apparatus for drawing glass cylinders, in combination, a bait, a drawing drum connected to said bait, a motor for driving said drum, an articulated air conduit pivoted at one end to the drawing head and at the other end to a fixed part but 15 adjustable longitudinally, a rheostat in the field circuit of the motor, and an extension on that member of the articulated conduit, next the fixed pivot, adapted to sweep over 20 the contacts of the rheostat as the position of said member last named is determined in accordance with the position of another member of said conduit as determined by the height of the drawing head.
- 25 8. In an apparatus for drawing glass cylinders, in combination, a bait, a drawing drum connected to said bait, an air conduit connected to said bait, a blower for supplying air to said conduit, a motor for driving both said drum and blower, and means for changing the speed of said motor when the bait is at different positions whereby to vary the rate of speed of the drum and bait for the different positions and to simultaneously 30 change the speed of the blower to either increase or reduce the air pressure generated thereby.
- 35 9. In an apparatus for drawing glass cylinders, in combination, a bait, a drawing drum connected to said bait, an air conduit connected to said bait, a blower for supplying air to said conduit, a motor for driving both said drum and blower, and automatically-operating means for changing the speed of said motor when the bait is at different positions whereby to vary the rate of speed of the drum and bait for the different positions and to simultaneously 40 change the speed of the blower to either increase or reduce the air pressure generated thereby and supplied through said conduit to the bait.
- 45 10. In an apparatus for drawing glass cylinders, in combination, a drawing head, a drawing drum, a motor for driving said drum, a blower, a conduit between the blower and the drawing head, means for connecting said blower to said motor, means whereby the speed of the motor is determined in accordance with the position of the drawing head, whereby the rate of draw and the rate of air feed are determined accordingly, and additional means whereby the rate of air feed through the conduit may 50 be controlled.
- 55 11. In a machine for drawing glass cylinders, in combination, a drawing head, a drawing drum, a motor connected to drive said drum, a reversing switch in circuit with the armature of said motor, a blower, an air conduit from said blower to said drawing head, and means for connecting said blower to said drum whereby when the switch is reversed to reverse the drum to lower the drawing head, the blower may be disconnected. 70
- 60 12. In an apparatus for drawing glass cylinders, in combination, a carriage, a winding drum connected to raise and lower said carriage, a motor for driving said drum, stationary means for regulating said motor, and an arm connected to and actuating said stationary motor-regulating means and having one end pivotally supported on and moving with said carriage. 80
- 65 13. In an apparatus for drawing glass cylinders, in combination, a drawing carriage, a bait supported on said carriage, a conduit having one end pivotally supported on and moving with said carriage for supplying air to said bait, a blower at the other end of said conduit, a drawing drum connected to raise and lower said carriage, and a motor for driving both said drawing drum and blower. 90
- 70 14. In an apparatus for drawing glass cylinders, in combination, a drawing carriage, an air conduit having one end pivotally supported on and moving with said carriage, a bait removably and adjustably supported on said carriage and adapted to swivel on a horizontal axis, said bait being in communication through the swiveling connection with said air conduit, a blower for supplying air to said conduit, a drawing drum connected to raise and lower said carriage, and a motor for driving both said drawing drum and blower. 100
- 75 15. In a glass drawing apparatus, a drawing means, a high speed motor connected to drive said drawing means at low speed and a blowing means driven at high speed by said motor, the blowing means being arranged to discharge through the drawing means. 110
- 80 16. A glass drawing apparatus including in combination a drawing means, a high speed motor connected to drive said drawing means at low speed, a blowing means driven at high speed by said motor, and a control for regulating the speed of said motor, said drawing means and blowing means adapted to vary in speed simultaneously in accordance with variations in the motor speed, the blowing means being arranged to discharge through the drawing means. 120
- 85 17. A glass drawing apparatus including in combination a drawing means, a high speed rotary motor, means connecting said 130

drawing means to said high speed motor whereby the drawing means may be driven at relatively low speed, a high speed rotary blower, connections from said blower to said drawing means, means whereby the high speed blower may be connected to the high speed motor, and a control directly modifying the speed of said motor and indirectly varying the speed of both said drawing means and rotary blower.

18. A glass drawing apparatus including in combination a drawing means, a motor adapted to drive said drawing means at a requisite drawing speed, a blower forming an independent structure and functioning separately from the motor, connections from said blower to the article being drawn, means whereby said independent blower may be driven by said motor, and means for regulating the speed of the motor.

19. A glass drawing apparatus including in combination an electric motor, drawing

means, air pressure generating means, means whereby said motor may simultaneously drive both said drawing means and said air pressure generating means, and a disconnecting member between said motor and the drawing means, and means for connecting said air pressure generating means to the object being drawn.

20. In a glass drawing apparatus, an electric motor, a drawing means, an independent air pressure generating means, means whereby said motor may simultaneously drive both the drawing means and the air pressure generating means, means for connecting said air pressure generating means with the object being drawn, and independent means for varying the control of air supply and the motor speed.

In testimony whereof, I affix my signature.

ARTHUR E. SPINASSE.
